Specification for Design.

Patented Feb. 22, 1921.

Application filed June 15, 1920. Serial No. 389,244. Term of patent 14 years.

To all whom it may concern:

Be it known that I, GEORGE K. GUINZBURG, a citizen of the United States, residing in the city, county, and State of New York, have invented a new, original, and ornamental Design for Garment-Protectors, of which the following is a specification, reference being had to the accompanying drawing, forming part hereof, in which—

I claim:

The ornamental design for a garment protector, as shown.

GEO. K. GUINZBURG.
